Attorney.

UNITED STATES PATENT OFFICE.

CLARENCE C. CRISS, OF ARKANSAS CITY, KANSAS.

GARMENT HANGER.

Continuation of application Serial No. 747,761, filed November 24, 1924. This application filed September 24, 1925. Serial No. 58,348.

To all whom it may concern:

Be it known that I, CLARENCE C. CRISS, a citizen of the United States, residing at Arkansas City, in the county of Cowley and

- 5 State of Kansas, have invented certain new and useful Improvements in Garment Hangers, of which the following is a specification, reference being had therein to the accompanying drawing.
- 10 The present invention relates to garment hangers, and aims to provide a hanger for trousers, skirts, and other garments, comprising a novel construction and assemblage of the component elements, this application being a continuation of application Serial No. 747,761, filed Nov. 4, 1924.

Another object of the invention is the provision of a garment hanger comprising clamping bars or jaws, hingedly connected 20 members carrying said bars or jaws, and novel means for holding said members and bars or jaws together to clamp the garment and operable in a convenient manner to release the bars or jaws so that they can be 25 separated for the insertion or removal of the garment.

With the foregoing and other objects in view, which will be apparent as the description proceeds, the invention resides in the 30 construction and arrangement of parts as hereinafter described and claimed, it being understood that changes can be made within the scope of what is claimed, without departing from the spirit of the invention.

35 The invention is illustrated in the accompanying drawing, wherein—

Figure 1 is a side elevation of the improved garment hanger.

Fig. 2 is an end view thereof.

40 Fig. 3 is a horizontal section on the line 3—3 of Fig. 2, portions being broken away.

Fig. 4 is a section detail on the line 4—4 of Fig. 1.

45 Fig. 5 is a perspective view of the suspending hook or member.

The garment is held between a pair of horizontal clamping bars or jaws 10 of wood or other suitable material, which are formed with concaved recesses 11 in their adjacent

50 or confronting sides between the ends of the bars, in order to accommodate seams or folds of the garment, so that the garment can be clamped between the opposite end portions of the bars when the portion of the garment 55 at the center of the bars is of greater thick-

ness due to seams, folds or doubled portions, which are accommodated by the recesses 11. If desired, one bar can have the recess and the other bar can be plain (with the recess omitted) to cheapen the cost of manufacture.

The bars or jaws 10 are carried by the members 12 and 13 formed from stout wire. Said wire members have the upstanding loops 14 and 15, respectively, and the lower 65 diverging terminals 16 formed with eyes 17 engaging rivets 18 or other securing elements that engage through the bars 10 near the ends of said bars, to clamp the eyes 17 against the outer or opposite sides of said 70 bars.

The upper yoke or cross portions of the loops 14 and 15 and a suspending hook or member 19 are hingedly connected, to enable the members 12 and 13 to be swung toward 75 and away from one another and to be suspended by the hook or member 19. The member 19 is also formed from stout wire, and the shank thereof has the angularly or horizontally extending portion 21 bearing 80 on a band 20 that embraces the yoke or cross portions of the loops 14 and 15. The member 19 has a bent back portion 22 below the portion 21 disposed between the yoke or cross portions of the loops, and said member 19 has another bent back portion 23 below the portion 22 extending under the band 20 and formed with an eye 24 embracing one limb of the loop 14, thereby rigidly connecting the hook or suspending member 19 90 and the member 12, leaving the member 13 free to be swung relatively to the members 12 and 19. By engaging the hook or member 19 over a supporting rail, bracket, or other supporting member, the garment 95 hanger may be suspended as usual.

In order to hold the bars or jaws 10 together so as to clamp the garment between them, a U-shaped latch 25 is provided, being formed from stout wire, and straddling the 100 loop 15. The terminals of the latch 25 are bent into hooks or eyes 26 engaging loosely through coils or eyes 27 with which the limbs of the loop 14 are provided, permitting the latch 25 to be swung upwardly and downwardly about a transverse axis extending through the eyes 27. The limbs of the loop 15 are provided with offsets 28 extending at an angle so as to project between 105 and across the limbs of the loop 14 when 110

the bars 10 are brought together, and when members having hingedly connected loops with depending limbs, jaws carried by the lower ends of said limbs of the two members, the limbs of one loop having offsets 65 between the hinge and jaws extending toward the other loop and adapted to extend across the limbs of said other loop when the jaws are moved together, and a latch hingedly connected to the secondnamed loop 70 and straddling the firstnamed loop and adapted to be swung into said offsets to permit said members to be swung apart, the limbs of the firstnamed loop having cam portions extending from said offsets for the 75 engagement of said latch when swung out of said offsets in order to clamp the jaws together.

5 10 to be swung apart for inserting the garment between or removing it from the bars 10. However, the latch 25 entering the offsets 28 will limit the separation of the members 12 and 13. The limbs of the loop 15 15 are curved, as at 29, immediately below the offsets 28 to form cams for the engagement of the latch 25, in order that when said latch is swung downwardly from the offsets 28 it will ride over the cam portions 20 25 so as to force the members 12 and 13 toward one another in order to clamp the garment between the bars 10. Thus, after the garment has been placed between the bars 10, with the bars 10 separated and the 20 latch 25 in the offsets 28, the garment is quickly and conveniently clamped between the bars 10 by simply swinging the latch 25 downwardly over the cam portions 29, from the dotted line position to the full line position as seen in Fig. 2. In order to release the garment from the hanger it is only necessary to swing the latch 25 upwardly into the offsets 28, which permit the bars 10 to be separated.

25 30 As seen in Figs. 1 and 3, the coils or eyes 27 form helical or spiral cams against which the limbs of the latch 25 contact, so that when the latch 25 is swung upwardly into the offsets 28, as seen in dotted lines in Fig. 35 40 2, the cam action between the limbs of the latch 25 and eyes 27 will have a tendency to spread the limbs of the latch 25 apart or to force the limbs of the loop 14 toward one another, which yielding action is permitted due to the fact that the parts are of resilient material. This yielding action has a tendency to swing the latch 25 downwardly by cam action between the eyes 27 and limbs of the latch 25, so that when the members 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 Having thus described the invention, what is claimed as new is:—

1. A garment hanger comprising two wire

members having hingedly connected loops with depending limbs, jaws carried by the lower ends of said limbs of the two members, the limbs of one loop having offsets 65 between the hinge and jaws extending toward the other loop and adapted to extend across the limbs of said other loop when the jaws are moved together, and a latch hingedly connected to the secondnamed loop 70 and straddling the firstnamed loop and adapted to be swung into said offsets to permit said members to be swung apart, the limbs of the firstnamed loop having cam portions extending from said offsets for the 75 engagement of said latch when swung out of said offsets in order to clamp the jaws together.

2. A garment hanger comprising a pair of hingedly connected members, one of which is composed of wire and provided with two coils forming eyes having cam surfaces, jaws carried by said members, and a U-shaped latch having its terminals 80 hingedly engaged in said eyes, the other member having a cam portion, said latch straddling the lastnamed member to engage said cam portion and clamp the jaws together, and said cam surfaces engaging the limbs of said latch to obtain yielding action of said latch and firstnamed member when the latch is swung out of engagement from said cam portion and to swing the latch into engagement with said cam portion when said members are pressed together.

3. A garment hanger comprising two wire members having hingedly connected loops with depending limbs, jaws carried by the lower ends of said limbs of the two members, the limbs of one loop having coils forming eyes having cam surfaces, the limbs of the other loop having offsets between the hinge and jaws extending toward the firstnamed loop, and a latch having its terminals 100 hingedly engaging in said eyes, said latch straddling the secondnamed loop and being adapted to be swung into said offsets to permit said members to be swung apart, the limbs of the secondnamed loop having cam portions extending from said offsets for the 105 engagement of said latch when swung out of said offsets in order to clamp the jaws together, and said cam surfaces engaging the limbs of said latch and so arranged as to obtain a yielding action of said latch and firstnamed loop when the latch is swung into said offsets and to swing the latch into engagement with said cam portions when said members are pressed together.

In testimony whereof I hereunto affix my 120 signature.

CLARENCE C. CRISS.
